Attorneys

UNITED STATES PATENT OFFICE.

DANIEL H. SNYDER, OF SNYDERVILLE, OHIO.

TIE FOR RAILS.

1,188,503.

Specification of Letters Patent. Patented June 27, 1916.

Application filed April 24, 1916. Serial No. 93,045.

To all whom it may concern:

Be it known that I, DANIEL H. SNYDER, a citizen of the United States, residing at Snyderville, in the county of Clark and State of Ohio, have invented certain new and useful Improvements in Ties for Rails, of which the following is a specification, reference being had therein to the accompanying drawing.

10 This invention relates to ties for rails.

An object of the invention is to provide a tie which is cheaper and more durable than the usual wooden tie and yet retains the advantages of the latter.

15 Another object of the invention is to devise a method for utilizing a block such as is used in connection with the metallic cross tie so that there may be no waste of the material thereof and all of the available portions can be utilized and worn.

20 In the accompanying drawings, Figure 1 is a plan view of the improved tie with parts broken away to show the drainage holes; Fig. 2 is an elevation of the same; Fig. 3 is 25 a section on the line 3—3 of Fig. 1, looking in the direction of the arrows; and Fig. 4 is a section on the line 4—4 of Fig. 1, looking in the direction of the arrows.

25 In the embodiment of the invention here shown the tie is constructed preferably of metal, although any other cheap and durable material may be used, and comprises a central portion 1 which has four sides and is of a tubular nature. A transverse partition 2 closes each end of this tubular portion, the partitions being spaced inwardly from the ends of the tie some distance, forming end compartments 3 to receive blocks 4 of any suitable material, such as wood. Each compartment is open at the outer end and top and closed at the bottom and sides. The blocks are of a width and thickness which correspond to the usual width and thickness of wooden ties now in use and are of a length 40 greater than three times the width of the flanges 5 of the rails 6 which rest upon the same. The blocks entirely fill the compartments 3 and extend from the ends to the partitions 2. The blocks are held in place 45 by suitable means and for this purpose the sides of the compartments are provided with openings 7 through which screw-threaded bolts 8 extend and press into the sides of the blocks to hold them in place, as shown at 9.

50 The location and arrangement of these bolts are such that the blocks are in no manner

weakened, as where nails and spikes are driven into the same at the top. The indentations which are formed in the blocks along the sides thereof are amply protected from 55 the weather and elements whereby the wearing qualities of the blocks are increased. As shown in the drawing, the flanges rest upon the blocks adjacent their inner ends and for this reason the inner portions of the compartments are recessed, as shown at 10. The blocks extend above the recesses and the recesses are sufficiently wide to miss the flanges of the rails so that the rails will rest entirely upon the blocks. By insuring a 60 substantial length of block between the flange and the end of the tie the resiliency and ease with which trains can travel over the track is facilitated and not diminished, as is usual in constructions which contain 65 metal and other material dissimilar to wood. When the portions of the blocks under the flanges shown in the drawing are worn down to the level of the metal part, the bolts 8 are loosened and each block turned over 70 so that the material on the opposite side of the same end is presented at the top to form a new wearing surface for the flange. When this last surface is worn down to the metal 75 the block is removed and the opposite end 80 inserted so that the flange will rest upon one side thereof and as this is worn down the block is again reversed to allow the flange to rest upon the fourth portion of the block. When both sides of both ends have 85 worn down a portion of one end of the block is sawed off, the intermediate portion on one side is worn down and then the other side of the intermediate portion is utilized. It will be seen that my arrangement of 90 metallic tie for the blocks and the particular size of the blocks insures that each block can be used six times at least. Of course, the steps described above can be multiplied by 95 using blocks of greater length.

100 To increase the wearing qualities of the blocks I eliminate entirely the spikes which are usually driven into the same and engage the flange to hold the rail in place. I have provided upon each side of each compartment two clamps 11 arranged to engage each side of the flange adjacent thereto. These clamps are provided with slots 12 into which bolts 13 project, whereby the clamps are adjusted. The bolts extend through the 110 sides of the compartments 3, the sides being recessed, as shown at 14, so that the inner

ends of the bolts will be flush therewith. The clamps are locked in position by means of nuts 15 and washers 16, substantially as shown. The clamps are provided with projecting portions or hooks 17 in engagement with the flanges. In order to keep the clamps in proper alinement I have provided elongated vertically extending guideways or stops 18 which engage the sides of the clamps remote from the flange and which guide the clamps and hold them in position. The bottom of the tie is provided with a series of apertures or openings 19 to allow the escape of water and moisture.

15 In the use of my tie it is contemplated to plant the same along the roadbed, as is usual in the case of wooden ties, but it will be seen that when my tie is once planted there is no necessity for ever removing it as far as the 20 metallic portions thereof are concerned and thereby tearing up and destroying the efficiency of the roadbed. I have also provided blocks which fit snugly in the ends of my improved metallic tie and which extend 25 substantial distances to each side of the flanges of the rails, whereby the resiliency of the tie is not impaired and is practically the same as in the case of ties which are made entirely of wood. The portions of 30 the compartments 3 adjacent the rails are cut away so that the rails rest entirely upon the blocks. I wish to lay special emphasis upon the novel method that I propose of utilizing these blocks and of making them 35 of such length that they can be used six or more times. By this method the cost of material is substantially reduced and the expenditure for tie blocks is much less.

Another feature which adds to the wearing 40 quality of the block is my way of fastening the same to the metallic portions. It has been usual heretofore to fasten the wood at the top by clamping means or by driving spikes through the wood at the top for holding the same. The means I employ forms indentations in the wood which are so small and are located at such a position that the weather has very little effect thereupon.

Another novel feature of my invention is 50 the manner of clamping the flanges to the blocks by which the spikes usually driven into the blocks are entirely eliminated. I provide guideways 18 which prevent the rotation of the clamps and hold them in 55 proper position.

The above construction provides for a special block of such dimensions that all the available portions thereof can be utilized and worn by the method above described.

60 While I have shown and described one embodiment of my invention it will be understood that this has been chosen for the purposes of illustration only, and that I do

not desire to be limited to the details of construction, shown and described, for obvious 65 modifications will occur to a person skilled in the art.

Having thus fully described my invention, what I claim as new and desire to secure by Letters Patent, is:—

1. In a tie, a body portion, end compartments, blocks located in said compartments and filling the same, clamping devices adjustably mounted on the outside of said compartments and engaging the flanges of the 75 rails, said clamping devices comprising body portions, slots in said body portions and bolts fixed to the sides of the compartments and projecting into the slots.

2. In a tie, compartments, blocks mounted in said compartments, clamping devices at each side of the compartments and in engagement with the flanges of the rails, said clamping devices having vertically extending slots, bolts mounted on the sides of the 85 compartments and projecting into the slots, and vertically extending guideways for said devices.

3. In a tie, a body portion, end compartments, a block mounted in each compartment and extending from end to end thereof, the inner portion of the block extending above the compartment so that the rail can rest entirely upon the block, means passing through the sides of the compartments and 95 engaging the sides of the blocks to hold the same in place, and adjustable clamps mounted on the sides of the compartments to engage the flanges of the rails.

4. The herein described method of utilizing end blocks for metallic ties which consists in wearing the block adjacent one end thereof on one side, turning the block over and allowing the other side of the same end to become worn, then inserting the other end 105 of the tie in the metallic tie structure and allowing one side of that to become worn and then reversing the same and allowing the other side of the last-mentioned end to become worn.

5. The herein described method of utilizing end blocks for metallic ties which consists in allowing one side of the end to be worn, then turning the block over and allowing the other side to become worn, reversing the block and allowing one side of the reverse end to become worn, then turning the block over and allowing the other side of the last-mentioned end to become worn, then sawing the block adjacent one 120 end and inserting the intermediate portion of the original block under the flange to allow that to become worn.

In testimony whereof, I affix my signature.

DANIEL H. SNYDER.
